(57) **CLAIM**

The ornamental design for an automotive wheel, as shown and described.

DESCRIPTION

FIG. 1 is a perspective view of an automotive wheel, showing my new design;

FIG. 2 is a front view thereof;

FIG. 3 is a perspective view of a second embodiment of an automotive wheel; and,

FIG. 4 is a front view of FIG. 3.

The broken line showing of the rear portion of the wheel is included for the purpose of illustrating environment and forms no part of the claimed design.
